UNITED STATES PATENT OFFICE.

JAMES R. SMITH, OF CHICAGO, ILLINOIS, ASSIGNOR TO HENRY C. BUHOUP,
OF SAME PLACE.

FIRE-EXTINGUISHING APPARATUS.

SPECIFICATION forming part of Letters Patent No. 314,887, dated March 31, 1885.

Application filed March 2, 1885. (No model.)

To all whom it may concern:

Be it known that I, JAMES R. SMITH, of Chicago, in the county of Cook and State of Illinois, have invented a new and useful Fire-
5 Extinguishing Apparatus; and I do hereby declare that the following is a full, clear, and exact description thereof.

My invention has reference to vessels designed to hold fluids which are to be forced 10 out by means of a pump, and is preferably used as a fire-extinguisher. I do not wish to be limited to such use.

My invention consists in a novel and convenient arrangement of a vessel for holding a 15 fire-extinguishing or other fluid, provided with one or more adjacent pockets or receptacles for holding additional charges of the chemical compound to be used when the fluid in the vessel proper is exhausted; also provided with a separate compartment or receptacle for holding a pump, when not in use, separate and apart from the corrosive effects of the chemical fluid, and also provided with an opening in its top through which to insert 20 the pump when necessary to discharge the fluid into the fire. By means of one or more springs provided with lugs and attached to the pump, and of one or more suitable openings in the mouth of the tank for the insertion 25 of the lugs, into which they will work automatically, the pump is securely fastened to the vessel when in use, and can be readily detached when necessary to withdraw the pump. Usually, when it requires a pump to force the 30 fire-extinguishing liquid into the fire the pump is attached to the vessel containing the liquid, and most often is a part of the apparatus itself. In such cases the pump remains in contact with the acids of the liquid, which corrode it, 35 and in time render it unfit for use in case of a fire. In the prior constructions which have separate pumps not normally in contact with the chemical solution the pump is provided with some stirrup attachment, making 40 it capable of easy use by one person for other purposes, while my means of attaching and operating the pump in this apparatus renders it incapable of use by one person for other purposes, for while one hand operates the 45 pump another holds the pump against the

suction of the piston, and another hand is required to direct the hose or nozzle. By my invention, while the pump is always with the apparatus, unless it is purposely removed, still it is kept out of the corrosive acids until 55 desired for use, and when desired for use is conveniently at hand.

In the accompanying drawings, Figure 1 shows my device ready for transportation to the fire, and with the side partially broken 60 away to show one of the cans containing the dry chemical compound in one of the adjacent pockets. Fig. 2 shows a vertical section of the same with the pump inserted in the vessel for use.

T is the tank or vessel designed to hold the fire-extinguishing or other liquid.

B' B² are pockets made to hold cans b b', containing extra charges of the chemical compound, to be used when the contents of the 70 tank are exhausted. Dry chemical compounds may be transported loosely in these pockets, being inclosed therein with a stopple or a top, without the necessity of the extra cans.

C is a separate chamber made to hold the 75 pump P. Any ordinary syringe or pump provided with suitable hose and of the proper dimensions can be used.

S S are springs securely attached to the sides of the pump, provided with lugs l l to fit 80 into the openings O O in the mouth of the tank, one or more of which can be used.

The apparatus can be transported by a handle or strap to fit the shoulders of the party carrying it.

When out of use, the pump is to be placed in the chamber C, where it is out of the way and in convenient position for transportation, and is not subject to corrosive effects of the acid if left in contact therewith in the same 90 vessel containing the fire-extinguishing liquid. By having the springs on the pump provided with lugs to fit in the openings O in the mouth of the tank, or with some similar device to securely fasten the pump to the tank while in 95 use, one man can easily use the apparatus. To this end I do not wish to be confined to the peculiar means shown to fasten the pump into the tank when in use. Any suitable means may be used.

100

If desirable, stirrups can be attached to the apparatus, on which the operator can place his feet when using the apparatus.

When necessary to use the fire-extinguishing liquid, the mouth of the tank is opened, the pump placed therein and secured to the tank by means of the springs and lugs working into the openings O, or by some other suitable means, and is then ready for use. Should the contents of the tank be exhausted, the chemical compound can be separated from the extra charges in the vessels in the pockets, and by the addition of water the contents will be again ready for use. One or more of these pockets can be used, as desired. This tank and the vessels containing the extra charges of the fire-extinguishing liquid, or the pockets themselves, if used without the cans, can be hermetically sealed, if the liquid is of such nature as that it will evaporate if exposed to the air; or they can be used with ordinary caps or any convenient stopples should the liquid be of such nature as that it does not require to be hermetically sealed.

Having thus described my invention, I claim and desire to secure by Letters Patent—

1. A portable tank for holding liquid provided with a pocket for holding a portable pump to be used in connection therewith and a central opening for filling, and in which said pump is secured when in use. 30

2. A fire-extinguishing apparatus consisting of a portable tank or bucket provided with a pocket for holding a portable pump and means for securing said pump in the mouth of such tank, and also provided with additional pockets to contain extra charges of dry chemicals, substantially as and for the purpose set forth. 35

3. A fire-extinguishing apparatus consisting of a vessel or tank provided with one or more openings, O O, in its mouth, in combination with a pump provided with one or more springs, with lugs arranged to fit into said openings, substantially as and for the purposes shown. 40

JAMES R. SMITH.
